MACHINE FOR OPENING HINGED CLOSURE MEMBERS ON CONTAINERS

Ronald E. J. Nordquist, Maplewood, N. J., assignor to American Can Company, New York, N. Y., a corporation of New Jersey

Application January 31, 1950, Serial No. 141,538

8 Claims. (Cl. 226—129)

1

The present invention relates to a machine for opening or loosening closure members on containers and has particular reference to devices for opening closure members which are crimped over a projecting ledge of the containers. This is an improvement on the machine disclosed in United States Patent 2,420,642 issued May 20, 1947, to August E. Almgren on Treating Machine for Opening Hinged Closure Members on Containers.

In the manufacture of fibre containers for milk and certain other liquid products, considerable care is taken to maintain the containers in a sterile condition. Toward this end the completed containers before shipment to the dairy for filling are sterilized and their closure members closed and sealed to protect the interior of the containers against contamination during shipment and handling. To insure against inadvertent opening of the closure members during shipment and handling of the containers, the protecting lips or flanges of the closure members are crimped under the projecting ledge of the containers. This crimped lip or flange causes some difficulty in opening the closure members immediately prior to filling the containers at the dairy.

The instant invention contemplates overcoming this difficulty by the provision of devices for loosening or releasing the crimped lips of the closure members from the containers to facilitate the complete opening of the closure members.

An object of the invention is the provision in a machine for opening closure members on containers, of decrimping or unsealing devices wherein crimped-over edges of the closure members may be readily loosened, unfolded and released from the containers to permit easy opening of the closure members and to prevent distortion or other injury to the closure members during the opening operation.

Another object is the provision of such decrimping devices which are adapted to automatic high speed operation so that the usual handling of the containers through filling machines will be unimpaired.

Numerous other objects and advantages of the invention will be apparent as it is better understood from the following description, which, taken in connection with the accompanying drawings, discloses a preferred embodiment thereof.

Referring to the drawings:

Figure 1 is a front elevation of a container opening machine embodying the present invention with parts broken away;

2

Fig. 2 is an enlarged fragmentary vertical section taken through that part of the machine shown at the left in Fig. 1;

Fig. 3 is a fragmentary sectional view taken substantially along the line 3—3 in Fig. 2;

Fig. 4 is an enlarged perspective view of the upper end of a container to be opened in the machine shown in the drawings; and

Figs. 5 and 6 are part elevational and part sectional views taken substantially along a vertical plane indicated by the line 5—5 in Fig. 2, with parts broken away, the two views showing certain of the movable parts of the machine in different positions.

15 As a preferred or exemplary embodiment of the invention, the drawings illustrate principal parts of a container opening machine of the character disclosed in the above mentioned Almgren Patent 2,420,642, for reopening sterile closed empty fibre milk containers A (Fig. 4) as an incident to filling the container with milk. The container A illustrated in Fig. 4 is similar to that disclosed in United States Patent 2,085,979 issued July 6, 1937, to John M. Hothersall on Container. This container comprises a rectangular shaped body B (Fig. 4) having its upper end formed with an inwardly extending tapered bead or neck C terminating in an outwardly projecting flange which envelopes a marginal portion of a flat top member or disc E forming with the latter a projecting ledge D.

The top member E is formed, in one corner thereof, with a filling and dispensing opening which is sealed by a friction plug closure member F hingedly secured by a wire staple G to the container top member E. The closure member F is formed with an outer lip or flange H which extends over the ledge D of the container along portions of two adjacent and converging sides thereof and which preferably is bent inwardly or crimped under the ledge D during the manufacture of the container to maintain the closure member F in a closed position during shipment and storage to insure against contamination of the sterile interior of the container.

The closure member F remains in the closed position from the time the container is finished at the factory until immediately prior to the filling of the container at the dairy at which time the crimped-under lip H is pried loose and the closure member is hinged open to gain access to the interior of the container. It is to the loosening or unsealing of the crimped-in lip H that the instant invention is particularly directed.

Reference should be had to the above mentioned Almgren Patent 2,420,642 for a detailed description and explanation of the machine, principal parts of which are herein illustrated, for opening the closure members F of the containers A. In this machine, the containers A are received in a horizontal position, with their top members E facing inwardly and with their closure members F extending upwardly as shown in Fig. 2 in alignment with the decrimping devices hereinafter described. In this position of a container, its closure member F is gripped by a suction cup 11 (Fig. 2) and held stationary. While the closure member is so gripped, the container is swung downwardly into a vertical position as shown at the right in Fig. 1, and thus the closure member F is opened by this swinging action of the container while at the same time the container is brought into filling position. This swinging of the container is effected while it is carried through a circular path of travel. The release or prying loose of the crimped lip H of the closure member is effected while the container is in its horizontal position as will be hereinafter explained.

The suction cup 11 (Fig. 2) for gripping the closure member F of a container A is carried on a rotatable turret 12 (see also Fig. 1) which is mounted on a column 13 of a frame 14 which constitutes the main frame of the machine. The turret is rotated in any suitable manner as disclosed in the above mentioned Almgren patent. The containers A are received in their horizontal position as explained above, adjacent the suction cup 11, in a carriage or cradle 16 (Figs. 1 and 2) which at its inner end is carried on a pair of pivot pins 17 secured in a pair of lugs 18 which depend from the turret 12. Adjacent the pivot pins 17, the cradle carries a cam roller 19 which operates in a groove 21 of a stationary cam 22 secured to the frame 14. The cradle 16 projects into a curved runway 24 defined by a plurality of curved guide rails 25 disposed adjacent the outer periphery of the turret 12.

The cradle 16 is in a horizontal position as shown in Fig. 2, when it receives its container A and as the cradle moves forward it temporarily remains in this horizontal position until clear of the usual container feed-in devices. It is during this period in the cycle of operation of the machine that the lip H of the closure member F is pried loose to facilitate opening of the closure member.

The prying loose of the lip H is effected preferably by a pair of slender fingers 31 (Figs. 3, 5 and 6) which are disposed on opposite sides of the suction cup 11 and which are aligned with the lower face of the flange or ledge D of the container disposed in its cradle 16. These fingers 31 preferably are formed on and project inwardly from a pair of toggle lever arms 32 which extend up adjacent an outer vertical peripheral wall section 33 of the turret 12. At their upper ends, both of these toggle lever arms 32 are mounted on a single pivot pin 34 which is secured in a slide block 35 carried in a vertical slideway 36 formed in the turret wall section 33. The inner end of the pivot pin 34 carries a cam roller 37 which operates in a cam groove 38 of a stationary barrel cam 39 on the frame 14. This cam actuates the fingers 31 as will be hereinafter explained.

Control of the fingers 31 during their movement is effected by a pair of stationary pins 41 which are secured in the turret wall section 33. These pins operate in curved cam slots 42 (Figs. 5 and 6) formed in the toggle lever arms 32 intermediate the ends of the arms. A face plate 43 75

secured to the turret wall section 33 retains the toggle lever arms 32 in place against displacement from the pivot pin 34 and the control pins 41.

5 The toggle lever arm actuating cam 39 is formed in such a manner as to lift and immediately lower the cam roller 37 during the period of the cycle of operation of the machine that the cradle 16 is moving in its horizontal position as mentioned above. On the up stroke of the cam roller 37, it lifts the pivot pin 34 and the toggle lever arms 32 from the position shown in Fig. 5 to that shown in Fig. 6. During this lifting of the toggle lever arms, the cam slots 42 slide inwardly on the stationary control pins 41 and this moves the fingers 31 inwardly toward each other.

In effecting this inward movement, the slender ends of the fingers 31 travel along the outer side 20 walls of the container A disposed in the cradle 16 and held by the suction cup 11, and engage under the crimped-in lip H and pry the lip loose from opposite sides thereof as the fingers continue to move inwardly. At the completion of the prying 25 operation, the fingers 31 are disposed as shown in Fig. 6 and the lip H is loosened or pried out to an extent at least in alignment with the outer edge of the container flange or ledge D as shown in Fig. 6.

30 Following this lip prying operation, the cam roller 37 immediately moves down into its original position and thus spreads the toggle lever arms 32 apart as shown in Fig. 5. This action forces the fingers 31 outwardly and withdraws them 35 from the container and thus completes the lip prying operation. As soon as the fingers 31 are free of the container, the latter starts its downward travel into a vertical position to open the closure member F as disclosed in the Almgren 40 patent above mentioned. With such a construction of lip prying devices the lip H is protected against damage during the closure member opening operation so that the lip may be used again, after the container is filled, to lock the closure member in place during shipment of the container to the consumer.

It should be understood that the application of 45 the lip prying device to the above mentioned machine disclosed in the Almgren Patent 2,420,642 is by way of example and as an improvement on the Almgren machine. If desired the lip prying device may be used independently of any machine or as an auxiliary to a machine for treating containers.

50 It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

65 1. In a machine for opening closure members having a flexible portion crimped over a projection of a container, the combination of a support for said container, a reciprocable mounting disposed adjacent said support, a finger carried on said mounting and insertable between said crimped portion of the closure member and said projection on said supported container, and means for bodily reciprocating said mounting to insert the finger between said crimped portion and 70 said projection and to move it along therebe-

tween for prying said portion loose from said container projection.

2. In a machine for opening closure members having a portion crimped over a projection of a container, the combination of a wall section, a support for a said container, a bodily movable mounting on said wall section adjacent said support, a finger movably carried by said mounting and projecting toward the crimped portion of the closure member on said supported container, and means for bodily moving said mounting on said wall section and said finger relative thereto for inserting the finger under said crimped portion to pry said portion loose from the container while said closure member is temporarily held in closed position to facilitate subsequent opening of said closure member.

3. In a machine for opening closure members having a portion crimped over a projection of a container, the combination of a support for a said container, a mounting slidably carried adjacent said support, a finger pivotally secured on said mounting and projecting toward the crimped portion of the closure member on said supported container, and means for slidably moving said mounting to pivotally move said finger relative thereto for inserting the finger under said crimped portion for prying said portion loose from the container while said closure member is temporarily held in closed position to facilitate subsequent opening of said closure member.

4. In a machine for opening closure members having a flexible portion crimped over a projection of a container, the combination of a support for said container, means for gripping the closure member on a supported container and for temporarily maintaining said member in closed position, a finger reciprocably mounted adjacent said support and projecting toward the crimped portion of the closure member, means for reciprocating said finger to insert the finger under and to move it along said crimped portion for prying said portion loose from the container to facilitate subsequent opening of said closure member, and means for relatively moving said container and gripping means to completely open the closure member.

5. In a machine for opening closure members having a portion crimped over a projecting ledge of a container, the combination of a support for a said container, an arm disposed adjacent said support, said arm adjacent one end having a finger projecting toward and in alignment with the crimped portion of the closure member on said supported container, said arm adjacent its opposite end being movable relative to said container for moving said finger, and guide means operable on said arm for guiding said moving finger into position under and along said crimped portion of the closure member for prying said portion loose from the container to facilitate opening of said closure member.

6. In a machine for opening closure members having a portion crimped over a projecting ledge

of a container, the combination of a support for a said container, a slide movable relative to said support, cam means for actuating said slide, an arm disposed between said slide and said support and having one end mounted pivotally on said slide, said arm at its opposite end having a finger projecting toward and in alignment with the crimped portion of the closure member on said supported container, and guide means operable on said arm intermediate its ends for guiding said finger into position under and along said crimped portion of the closure member for prying said portion loose from the container to facilitate opening of said closure member.

15 7. In a machine for opening closure members having a flexible portion crimped over a projection of a container, the combination of a support for a said container, means for gripping the closure member on a supported container and for temporarily maintaining said member in closed position, a finger projecting toward the crimped portion of the closure member on said supported container, said finger being insertable between said crimped portion and said projection and movable along said crimped portion for prying said portion loose from said projection while said closure member is temporarily held in closed position, to facilitate subsequent opening of said closure member, and means for relatively moving said container and gripping means to fully open said closure member.

20 8. In a machine for opening closure members having a flange portion crimped over a projecting ledge of a container, the combination of a support for a said container, a pair of toggle lever arms disposed adjacent said support, said arms adjacent their outer ends being connected together pivotally, said arms adjacent their inner ends having oppositely disposed fingers projecting toward and in alignment with opposite sides of the crimped portion of the closure member on said supported container, actuating means for moving said toggle lever arms in unison at their pivotally connected ends, and guide means operable on said arms for guiding the fingers on said moving arms into position under and along said crimped portion of the closure member in opposing directions for prying said portion loose from the container to facilitate opening of said closure member.

30 50 RONALD E. J. NORDQUIST.
